United States Patent Office

Des. 197,104
Patented Dec. 10, 1963

197,104

DOOR HANDLE

Ray C. Sandin, Winnetka, Ill., assignor to General
Electric Company, a corporation of New York

Filed May 3, 1963, Ser. No. 74,728

Term of patent 7 years

(Cl. D81—25)

FIG. 1 is a top plan view of a door handle showing my new design;

FIG. 2 is a side elevational view thereof;

FIG. 3 is a bottom plan view thereof;

FIG. 4 is an end elevational view thereof, each end being identical; and

FIG. 5 is a sectional elevational view thereof, looking in the direction of lines 5—5 of FIG. 2.

I claim:

The ornamental design for a door handle, substantially as shown and described.
